(57) **CLAIM**

The ornamental design for a display screen or portion thereof with animated graphical user interface, as shown and described.

DESCRIPTION

FIG. 1 is a first image in a sequence for a display screen or portion thereof with animated graphical user interface. FIG. 2 is the second image thereof; and, FIG. 3 is the third image thereof.

The appearance of the animated graphical user interface sequentially transitions between the images shown in FIGS. 1-3. The process or period in which one image transitions to another image forms no part of the claimed design.

The broken-line outer perimeter illustrates a display screen. The remaining broken lines illustrate portions of a graphical user interface. The broken lines form no part of the claimed invention.
